SPRAY GUN MOVER AND CONTROL

William C. Burt, Olean, N. Y., assignor to Clair
Manufacturing Company, Inc., Olean, N. Y.

Application January 11, 1951, Serial No. 205,529

9 Claims. (Cl. 51—263)

1

This invention relates to glazing, burnishing, polishing and buffing methods or the like as are useful in the industries in connection with the finishing of metal, plastic, wooden or other surfaces. More particularly, the present invention relates to improvements in means for transversely moving spray "guns" such as are used to distribute materials such as abrasives for example over surfaces such as glazing or polishing or buffing rolls requiring to be uniformly coated with sprayable material. The invention has particular application in conjunction with straight line reciprocating spray gun installations.

Whereas, in prior machines for the purposes aforesaid the spray gun has usually been permitted to spray its material during directional change halts and deceleration and acceleration phases of its traverse movements with consequent overloading of the sprayed surfaces at the ends of the gun travel path, the present invention contemplates control of the gun spray operation independently of the gun mover operation and complete cessation of the spraying operation during acceleration and deceleration and direction reversing movements of the gun. Also, in prior machines for the aforesaid purposes where the problem has been to spray relatively long polishing rolls, in order to avoid use of impractically long gun mover cylinders and travel rails two or more guns have been mounted in side-by-side relation upon the traverse motion frame so as to reduce the required length of the traverse stroke. Such installations have been found to be defective however because it is impossible to adjust the gun mover and spray control devices so as to prevent either overlapping or gapping of the spraying operations of adjacent guns, and in either case the surfaces being sprayed are overloaded in the regions where the guns are halted and accelerate and decelerate in their traverse movements incidental to reversal of their direction of travel. Also, in some prior machines for the purposes aforesaid the gun mover cylinder exhaust air has been used to feed the spray gun, and this introduces cylinder oil into the spray solution such as is not permissible when working for example with water base mixtures or emulsions, or the like.

One of the objects of the present invention is to avoid the difficulties and disadvantages aforesaid by providing improved means for mounting and moving a spray gun in straight line reciprocative manner and to control the spray operation of the gun so as to insure uniform coverage of the surface being treated despite necessary reversals of direction and changes of pace of the gun travel incidental to its reciprocation.

2

Another object of the invention is to provide in conjunction with a reciprocating spray gun an improved gun air control device whereby the gun discharge may be interrupted at the end of each stroke of the gun movement in improved manner so as to prevent incidental plugging of the gun whereby smooth and accurate operation of the gun and avoidance of abrasive "dripping" is assured to provide a uniform spray delivery pattern.

Another object of the invention is to provide a straight line reciprocating gun mover mechanism which is of improved compactness of form in relation to the length of traverse.

Another object of the invention is to provide in devices of the character aforesaid improved means for adjusting the mechanism to suit performance specifications.

Still another object of the invention is to provide in machines of the character described improved means for adjusting relatively moving parts to compensate for wearing thereof.

Other objects and advantages of the invention will appear in the specification hereinafter.

25 In the drawing:

Fig. 1 is a front elevation of a 2-roll polishing or glazing machine of a type such as is used in the cutlery polishing and glazing industries, having mounted thereon an abrasive spray "gun" mounting and moving and control mechanism of the invention;

Fig. 2 is a fragmentary section, on an enlarged scale, taken along line II—II of Fig. 1;

Fig. 3 is an enlarged detail of Fig. 2;

Fig. 4 is a fragmentary section taken along line 35 IV—IV of Fig. 3;

Fig. 5 is a front elevational view showing another form of spray gun actuating mechanism of the invention;

Fig. 6 is an enlarged detail of Fig. 5;

Fig. 7 is a fragmentary section, on an enlarged scale, taken along line VII—VII of Fig. 5;

Fig. 8 is a fragmentary section, on an enlarged scale, taken along line VIII—VIII of Fig. 6; and

Fig. 9 is a wiring control diagram for the machines of Figs. 1 and 5.

As stated hereinabove, the present invention relates to means for motivating and controlling operation of a spray gun or the like in conjunction with straight line reciprocative movements thereof for the purpose of effecting uniform distribution of the spray gun output over surfaces to be treated thereby. The invention is applicable to any industry but by way of exemplification it is illustrated and will be described in detail hereinafter in conjunction with machines employing

paired polishing or buffing rolls between which articles of manufacture are passed for finishing operations thereon while suitable polishing or buffing abrasive materials are fed by a "gun" onto the machine rolls. Thus, as shown in Fig. 1, a machine for such purpose may comprise a base structure 10 mounting bearing pedestals 12-12 which in turn carry parallel polishing or buffing rolls 14-14. Motors 15-16 are shown as being connected through suitable shafting to the rolls 14-14 for driving the latter to rotate so as to thereby provide a polishing or buffing gap as indicated at 17 between the rolls for passage therethrough of the work pieces to be surface treated, as is well known in the art. Such work pieces may be individually handled or mounted in "gangs" upon suitable frames or the like which are in turn mounted upon an upper carriage as indicated at 18 which is arranged to reciprocate from right to left, as viewed in Fig. 1. The carriage 18 is in turn mounted upon a lower carriage 19 which is mounted upon the base 10 by means of slideways 20-20 for reciprocation in directions transversely of the directions of reciprocation of the upper carriage 18. Thus, the work pieces will be mounted and arranged for simultaneous reciprocation in directions longitudinally of the polishing or buffing rolls and back and forth in and out of the polishing gap 17; the operative details of such a machine for this purpose being more fully disclosed for example in U. S. Patent No. 2,458,708.

A gun for spraying a suitable polishing or buffing abrasive (the various types of which are well known in the art) is illustrated at 25, and as illustrated in Figs. 1-2, the gun 25 may be mounted on the machine by means of a framing structure which extends from the pedestals 12-12 and which includes end plates 26-26 and a generally rectangular housing 28 which mounts at its opposite ends upon the end plates 26-26. A slideway 29 extending longitudinally of the housing 28 is fixed to the bottom plate thereof and engages a rack bar 30 in such manner that the latter is freely slidable longitudinally within the slideway 29 from right to left as viewed in Fig. 1, throughout the extent of the housing 28. A second rack bar 32 is fixed to the ceiling plate portion of the housing 28, and a spur gear 33 is disposed between the racks 30, 32 to simultaneously mesh with both racks. The gear 33 is connected by means of a pin and clevis device 34 to a piston rod 35 extending from a cylinder 36 which is mounted within the housing 28 and fixed thereto by means of an end bracket 37. Thus, it will be appreciated that movement of the piston within the cylinder 36 will procure corresponding displacements of the gear 33, thereby causing the latter to rotate and to drive the sliding rack 30 to move in the same directions as the piston movements but at twice the rate and to twice the extent of such piston movements.

A bracket as indicated at 40 is arranged to extend rigidly from the sliding rack 30 for mounting of the gun 25 and its control valve 42 thereon, so that both the gun 25 and its control valve will move with the sliding rack 30. This may be accomplished as shown by mounting the valve 42 directly on the bracket 40 and then arranging the valve outlet conduit as indicated at 44 to act as a mounting bracket for the gun 25 and also to convey compressed air to the gun. However, it will be appreciated that the gun and valve devices may be mounted in any other suitable manner relative to the moving rack 30 so that they will move with the rack while being at the same

time properly positioned for their intended functions as will be explained more fully hereinafter. In any case it will be understood that the arrangement will include provision for intake of compressed air for actuation of the gun, as by means of the conduit 44, and as well as provision for intake of the abrasive supply as indicated for example at 46. For this purpose the intake fitting 46 may connect to any suitable supply of abrasive, as is well known in the art.

The intake port of the valve 42 is indicated at 48 and is illustrated as being connected by means of a conduit 49 to a suitable compressed air supply line 50. Preferably, an air filter device of some suitable construction as indicated at 52 will be inserted in the supply line 50 ahead of the conduit 49, for the purpose of removing any oil or other foreign substance from the air leading to the spray gun, such as might become entrapped in the air at the air compressor or elsewhere.

The compressed air supply line 50 also leads through suitable connections to the cylinder 36 for two-way operation of the piston therewithin. For example, a two-way valve device as indicated at 54 may be arranged to control the flow of air from the line 50 into the cylinder 36; the armature of the valve 54 being controlled electrically to permit introduction of compressed air into the cylinder 36 alternately at opposite sides of the piston therewithin. Furthermore, the valve 54 will preferably be electrically operated so as to give the operator of the machine full stop-start control of the machine. Also, a pressure regulator as indicated at 56 and a lubricator as indicated at 58 will preferably be included in the line 50 ahead of the valve and cylinder 36 so that the air pressure on the cylinder may be manually regulated and so that the air feeding the cylinder 36 will be lubricated for proper maintenance of the cylinder-piston unit.

As shown in Fig. 1, the gun control valve 42 includes an actuating stem 59 which is arranged to be controlled by means of a cam roller 60 carried by a lever 61 which is fulcrumed upon the valve body. The cam roller 60 is in turn arranged to be actuated by a pair of cam spools 62-64 which are carried upon a rod 65 which is mounted at its opposite ends upon brackets 66-67 extending from the housing 28. The rod 65 is arranged to parallel the rack bar 30 so that the cam devices 62-64 come into registry with the cam roller 60 when the gun 25 reaches the opposite ends of its prescribed travel as it reciprocates in response to operation of the piston-cylinder unit 36. Thus, the gun is arranged for application of abrasive against the polishing or buffing rolls throughout the extent of their working areas. The cam devices 62-64 are arranged to be adjustable longitudinally on the rod 65 and to be locked thereon at any desired position of adjustment as by set screws 68 (Fig. 4).

Consequently, to set up the machine to process an article or a gang of work pieces of given width a pair of electrical limit switches 69-69 (Fig. 9) may be arranged to control solenoid-actuated cylinder valve 54; the limit switches being set so as to cause the piston rod 35 to move within such limits as will cause the rack 30 to reciprocate throughout a range extending at each end beyond the areas of the rolls requiring to be supplied with abrasive throughout the prescribed finishing operation. Then, the cam devices 62-64 will be individually adjusted longitudinally on the rod 65 so that they will coincide with the limits of the

range of travel of abrasive application by the gun 25 as carried by the rack 30.

The cam devices 62—64 are formed with sloping faces as indicated at 70, so that they will somewhat gradually lift the cam roller 60 as it reaches the desired limit of gun spraying; thereby gradually cutting off the flow of air to the gun as the gun reaches each end of its range of operation. This gradual closing of the valve 42 first reduces the air pressure in the gun 25 so as to deprive the gun of sufficient air pressure to continue the feeding of abrasive through the gun nozzle while a small flow of air continues for a short time to pass through the nozzle before the valve closes completely. This operates to clean the abrasive feed orifice of the gun incidental to each stoppage of the gun operation, and thus prevents undesirable plugging of the gun with abrasive material such as would otherwise cause abrasive to accumulate in the gun and to be subsequently forced out in gobs or driplets to cause uneven delivery of abrasive to the rolls.

Thus, in accord with the present invention, when the gun passes the area requiring spraying and prior to the time the gun reaches each end of its reciprocatory movement the abrasive supply to the gun 25 is shut off, while a small flow of air is momentarily permitted to clean the gun nozzle. This insures even application of abrasive to the working areas of the rolls and prevents undesirable piling up of abrasive on the rolls in the regions of the end limits of the gun travel back and forth along the rolls; and it will be appreciated that the cam devices 62—64 may be readily adjusted on the rod 65 so as to give exactly the proper timing of the gun shut off operations. Consequently, with a gun control mechanism of the present invention undesirable piling and caking of abrasive on the rolls and subsequent spalling off of caked abrasive from the rolls is prevented, and this avoids occurrence of alternately abrasive-coated and bare roll surfaces such as are so undesirable in connection with industrial finishing operations.

As shown in Figs. 3 and 4, further provision for fine adjustment of the cam devices relative to the valve actuating cam roller 60 is made in conjunction with the mounting connections of the outer ends of the rods 65 in the brackets 66 and 67. For example, as shown in conjunction with the bracket 66, the latter is apertured to receive a sleeve 72 which is eccentrically bored to receive the rod 65 therein. A shoulder 73 is formed on the rod 65, and it is threaded and provided with a nut and lock washer 74—75 at its outer end for cooperation with the shoulder 73 to lock the rod and sleeve firmly in the bracket 66. Thus, upon loosening of the nut 74, the sleeve 72 may thereupon be turned so as to displace the rod 65 thereby adjusting the vertical elevation of the cam device 64 which is carried by the rod. Provision of this type eccentric mounting at each end of the rod 65 permits the latter to be adjusted relative to the valve cam roller 60 so that any desired operation of the valve and gun devices may be accurately obtained.

Figs. 5 to 8 illustrate application of the invention in another manner to a polishing or glazing machine including side frame members 80—80 upon which are mounted polishing or glazing rolls 81—81 which correspond to the rolls 14—14 of the machine illustrated in Figs. 1—2. In Fig. 5 the abrasive spray gun is indicated at 82 and is carried by means of a compressed air inlet conduit 83—75

which extends from connection to the air outlet port of a control valve 84. The intake port of the valve 84 is connected to a compressed air supply conduit 85 which in turn leads into connection with a suitable supply of compressed air, such as the line indicated at 86. As shown in Figs. 5 and 7, the valve body 84 is mounted by means of studs 88 upon a cross head member 90 which is mounted to move within an elongate rectangular housing 92 which corresponds generally to the housing 28 of Figs. 1—2.

The cross head 90 is mounted to move freely within the housing 92 by means of rollers 93—94—95—96; and as shown in Fig. 8 the rollers are carried by axles 97 which are in turn carried within eccentrically bored sleeves 98. Lock nuts 99 lock the wheel and axle units upon the sleeves 98, and the latter are screwthread mounted upon the cross head 90 in such manner that the four rollers 93—94—95—96 are brought to bear respectively against the four inside wall portions of the rectangular housing 92 for supporting the cross head 90 in free rolling relation within the housing. Thus, it will be appreciated that the eccentric sleeve devices 98 are adapted to be turned as may be required to adjust the roller axles positionally relative to the cross head, so that the rollers may be thereby accurately positioned relative to the housing so as to support the cross head for free rolling movement therewithin without binding and without lost motions such as would permit the cross head to chatter when moving inside the housing. Thus, this eccentric roller mounting arrangement is useful in connection with initial assembly of the device as well as comprising means for compensating for wearing of the rollers or housing members, to insure precise non-chattering operation of the cross head.

The cross head 90 is fixed to one end of a piston rod 100 which extends into a cylinder 102 which is fixed to extend longitudinally within the housing 92. The cylinder 102 corresponds to the cylinder 26 of Figs. 1, 2 and is arranged to be controlled by means of a two-way valve 104 which corresponds to the valve 54 of Fig. 1. The valve 104 is fed by the air supply line 86, and as indicated at 106, 107, 108, air filter and pressure regulator and lubricator devices, respectively, are preferably installed in the line 86 ahead of the valve 104 for reasons explained hereinabove in connection with the mechanism of Fig. 1. As shown in Fig. 5, the valve 84 is arranged to be controlled by means of a roller arm 110 which is fulcrumed upon the valve housing and arranged to register with opposite cam spools 112—112 which are slidably mounted for adjustment upon a rod 114 carried by brackets 116—116 to extend alongside the housing 92 and parallel to the direction of cross head travel. The cam spools 112—112 are shaped to include sloping contact portions as in the manner of the cam spool 64—62 of Fig. 1 for purposes explained hereinabove. Also, the rod 114 is elevationally adjustable on the brackets 116—116 by means of eccentric locking sleeve devices 118 which are of type similar to the sleeve devices 72 shown and described hereinabove in connection with the arrangement of Figs. 1—4.

Thus, it will be appreciated that in the mechanism of Figs. 5 to 8, the spray gun is carried by a cross head device which is in turn connected directly to the actuating piston of the cylinder which procures reciprocation of the spray gun unit, as distinguished from the spray gun mounting method of Figs. 1—2 wherein an intermediate

gear and rack arrangement is employed to multiply the extent of spray gun travel responsive to piston movement. Thus, in the case of the mechanism of Fig. 5, the piston cylinder unit and the housing 92 must of necessity be of sufficient length to at least equal the length of the machine roll which is required to be sprayed with abrasive material, and in the case of relatively short polishing or buffing roll installations the spray gun mounting method of Fig. 5 is quite practicable. However, as explained hereinabove it will be appreciated that the arrangement of Fig. 1 provides for a path of spray gun travel which is twice as long as the extent of the corresponding piston movement within the cylinder 36; and thus, in the case of Fig. 1 a piston cylinder and housing unit may be designed to more compact form and is of particular advantage in connection with machines employing relatively long polishing or buffing rolls. In such cases the piston-cylinder and housing unit may readily be constructed not to exceed the overall width of the other portions of the machine.

However, it will be appreciated that in connection with the machines of both Fig. 1 and Fig. 5, the precise adjustability of the spray gun valve cam control action is attained whereby the machines may be readily adjusted so that the supply of abrasive is automatically reduced and cut off in the regions of the ends of the strokes of the spray gun as it travels back and forth alongside the rolls so as to avoid building up of undesirably heavy coatings of abrasive on the rolls at the ends of the spray gun strokes. Also, that the gun spraying operations at the ends of the reciprocatory strokes thereof are interrupted in an improved manner so as to avoid plugging of the gun jets and dripping of abrasive therefrom onto the polishing rolls such as would otherwise be inevitable incidental to interruptions of the gun spraying operations.

As explained hereinabove, whereas the drawing and the detailed description relates specifically to application of the invention to 2-roll glazing or polishing or buffing machines or the like, the invention is equally applicable to other devices wherein the problem is to move the spray gun to reciprocate and to at the same time apply a uniform coating of the sprayed material over the surface being treated. Thus, although only a few forms of the invention have been illustrated and described in detail, it will be understood to those skilled in the art that the invention is not so limited but that various changes may be made therein without departing from the spirit of the invention or the scope of the appended claims.

I claim:

1. In a spray gun mover mechanism a cross-head member arranged for mounting the spray gun thereon, means for reciprocating said cross-head member for carrying the spray gun in a traverse path, guide rail means paralleling the path of said cross-head in its reciprocative movements, roller means carried by said cross-head and bearing against said guide rail means for frictionless guiding of said cross-head, and eccentric bearing means mounting said roller means upon said cross-head and adjustable at will to displace said roller means relative to said cross-head for taking up any slack between said rollers and said guide way such as may be caused by wearing of the roller means or guide rail means.

2. A spray gun mover mechanism comprising 75 gun for operation of the latter, control means for

a stationary frame, guide rail means mounted on said stationary frame, a first gear rack mounted upon said guide rail means for longitudinal shifting movements thereon, bracket means extending from said first gear rack for mounting the spray gun thereon to reciprocate with said gear rack relative to said stationary frame, a second gear rack fixed to said stationary frame to extend in spaced parallel relation to said first gear rack, a gear disposed between said first and second gear racks to extend in meshing relation therebetween, and a powered push-pull member connected at one of its ends pivotably to the center of said gear and extending therefrom into connection with a push-pull power source, whereby displacements of said push-pull member will force said gear to be displaced relative to said fixed frame and to rotate due to its meshed connection with said second rack to thereupon drive said first gear rack to move at twice the rate of movement of said push-pull member.

3. A spray gun mover mechanism comprising in combination with a spray gun, a stationary frame, a movable structure including a reciprocating member mounting the spray gun to be reciprocatively movable therewith, power means connected to said member for moving the latter so as to reciprocate the gun across the area to be sprayed and slightly therebeyond at each end thereof, a variable delivery valve controlling inlet of compressed air to said spray gun for operation of the latter, control means for said valve, said valve and said control means being respectively connected to the stationary frame and to the movable structure and said control means being arranged to operate said valve to stand in open position while said spray gun is traversing the area to be sprayed and to close said valve after said spray gun reaches said ends of the area to be sprayed and prior to arrival of the spray gun at its limits of traverse travel, said valve control means including a pair of individually positionally adjustable cams determining said ends and having sloping faces for gradual closing of said valve as said spray gun moves beyond said ends.

4. In a spray gun mover mechanism a reciprocating member arranged for mounting a spray gun thereon, means for moving said member to reciprocate a spray gun thereon in a traverse path, rod means mounted by end bearings to substantially parallel the path of said member in its reciprocative movements, cam means carried by said rod member and adapted to be adjustably fixed thereon, flow valve control means carried by said member and bearing against said cam means for control of said valve, and eccentric sleeve devices mounting said end bearings upon said rod means, said sleeve devices being separately adjustable at will to displace said rod means relative to said member for adjusting the operation of said cam means.

5. A spray gun mover mechanism comprising in combination with a spray gun, a stationary frame, a movable member shiftable upon said frame for mounting the spray gun to be reciprocatively movable therewith, power means connected to said member for moving the latter so as to reciprocate the gun relative to said frame, adjustable limit means controlling said power means to cause said gun to traverse a selectable area to be sprayed and also an area therebeyond at the end of each gun traverse stroke, a valve controlling inlet of compressed air to said spray

said valve, said valve and said control means being respectively fixed to the stationary frame and to the movable member, and said control means being adapted to operate said valve to stand in open position while said spray gun is traversing the area to be sprayed and to close said valve when said spray gun reaches the end limits of the spray area and prior to arrival of the spray gun at its selected limits of traverse travel.

6. A spray gun mover mechanism comprising a stationary frame, a first gear rack mounted upon said frame for longitudinally shifting movements thereon, bracket means extending from said first gear rack for mounting the spray gun thereon to reciprocate with said gear rack relative to said stationary frame, a second gear rack fixed to said stationary frame to extend in spaced parallel relation to said first gear rack, a gear disposed between said first and second gear racks to extend in meshing relation therebetween, and a powered push-pull member pivotably connected at one of its ends to the center of said gear and extending therefrom into connection with a push-pull power source, whereby displacements of said push-pull member will force said gear to be displaced relative to said fixed frame and to rotate due to its meshed connection with said second rack to thereupon drive said first gear rack to move at twice the rate of movement of said push-pull member.

7. A spray gun mover mechanism comprising in combination with a spray gun, a member for mounting the spray gun to be reciprocatively movable therewith, a compressed air supply and a spray fluid supply for said gun, said fluid supply being regulated by the pressure of the air supplied to said gun, substantially constant speed hydraulic power means connected to said member for moving the latter so as to reciprocate the gun to traverse the area to be sprayed and to move therebeyond at each end of the spray area, a variable delivery valve in said compressed air supply controlling inlet of compressed air to said spray gun for operation of the latter, control means for said valve, said valve and said control means being respectively connected to the stationary frame and to the movable structure and said control means being arranged to operate said valve to stand in open position while said spray gun is traversing the area to be sprayed and to close said valve when said spray gun reaches the end limits of the spray area and prior to arrival of the spray gun at its limits of traverse travel, said valve control means including a pair of individually positionally adjustable cams each having a sloping contact face for slow closing of said valve as said gun moves beyond the end limits of said spray area, whereby the pressure of said air supplied to said gun is first reduced to terminate delivery of said fluid while continuing air flow through said gun and is then shut off to terminate operation of said gun.

8. In a spray gun mover mechanism a frame carrying a reciprocating member arranged for

mounting a spray gun thereon, means for reciprocating said member for carrying a spray gun thereon in a traverse path, rod means mounted by end bearings upon said frame to substantially parallel the path of said member in its reciprocative movements, separately adjustable paired cam means carried in spaced relation by said rod means, valve means carried by said member and bearing respectively against said cam means prior to arrival at opposite ends of the traverse stroke for control of said valve means, and eccentric devices mounting the ends of said rod means upon said end bearings, said devices being separately adjustable at will to displace said rod means relative to said member for adjusting the operation of the cams.

9. A spray gun mechanism comprising a stationary frame, a spray gun, a movable member reciprocable upon said frame and mounting said spray gun to be reciprocably movable therewith, said gun having a compressed air supply and a spray fluid supply, said fluid supply being regulated by the pressure of the air supplied to said gun, substantially constant speed fluid power means connected to said member for moving said gun relative to said frame, adjustable limit means controlling said power means to cause said gun to traverse a selectable area to be sprayed and also an area therebeyond at the end of each gun traverse stroke, rod means mounted by end bearings upon said frame to parallel the path of said member in its reciprocative movements, paired cams carried by said rod means and independently adjustably fixed thereon in spaced relation, a variable delivery normally open valve in said compressed air supply controlling inlet of compressed air to said spray gun for operation of the latter, a control arm for said valve, said valve arm being mounted for movement with said gun and to bear respectively against said cams for closing said valve, said cams being positioned on said rod means to engage said valve arm prior to arrival of the gun at opposite ends of its stroke, eccentric sleeve devices mounting said end bearings upon the ends of said rod means and separately adjustable at will to displace said rod means relative to said member for additionally adjusting the operation of the cams, said cams each having a sloping contact face for slow closing of said valve as said gun moves beyond the area to be sprayed, whereby the pressure of said air supplied to said gun is first reduced to terminate delivery of said fluid while continuing air flow through said gun and is then shut off to terminate operation of said gun.
